[57] **CLAIM**

The ornamental design for a faucet spout, as shown and described.

DESCRIPTION

FIG. 1 is a top perspective view, as viewed from the top right side, of a faucet spout showing our new design;

FIG. 2 is a right side view thereof, with the left side view being a mirror image;

FIG. 3 is a front view thereof;

FIG. 4 is a rear view thereof;

FIG. 5 is a top view thereof; and,

FIG. 6 is a bottom view thereof.

CERTIFICATE OF CORRECTION

Page 1 of 4

PATENT NO. : Des. 415,826
DATED : October 26, 1999
INVENTOR(S) : Costello, et al

It is certified that error appears in the above-identified patent and that said Letters Patent is hereby corrected as shown below:

The title page, showing the illustrative figure should be deleted and replace with the attached title page.

In the Drawings:

Delete drawing sheets consisting of Figures 1-6, and insert the following drawings consisting of Figures 1-6, per attached drawing sheets.

Signed and Sealed this

Thirty-first Day of October, 2000
